UNITED STATES PATENT OFFICE.

GEORGE M. B. HAWLEY, OF GENEVA, NEW YORK.

AUTOMATIC RAILWAY CONTROL.

Application filed January 9, 1918. Serial No. 211,061.

This invention relates to railway control, and has for its object to provide an improved system of control applicable either to cab signals, air brakes, power controllers, whistles, or other devices on a train whereby control on the train is effective by means outside of the train and independent of centrifugal governors, ramps, signaling third rails or other arrangements such as have heretofore 10 been proposed.

By this invention, there is provided what may be called a normal clear system wherein a device on the locomotive, such as a magnet, valve, or light, normally operates and indicates a clear condition, and which is to be thrown out of operation and replaced by a danger or a proceed indication only in accord with certain predetermined proceed or stop conditions. By a danger condition is 20 meant such a condition which under the rules and instructions requires that a train stop, while by proceed is meant such a condition as permits the train, under the rules and regulations, to proceed either at unlimited speed, 25 or a predetermined limited speed such as thirty miles per hour or upward, or a lower safety speed such for example as ten miles per hour.

In the case of a cab signal system without 30 speed control, the engineer receives visually or audibly or both, the exact duplication of the signals ahead which he is required to follow and he is supposed to be governed by them and to stop until given "clear" in case 35 of a "stop" signal. As a fundamental part of the cab signal system there is a "clearance" signal visual or audible or both, which represents "normal clear" as without it he has no clearance and must stop unless, as in 40 the speed control clearance, the clearance is cut out and substituted by control signals.

Also, the present system is of such elasticity that the proceed speed may be either limited to a predetermined amount, or unlimited, depending upon the performance 45 desired. By means of the system herein described, it is also possible to automatically signal the engineer, or slow down the train, or both, at predetermined points, such as at 50 a curve or weak place in the track, and the same means can be employed to automatically blow the whistle for highway crossings or similar situations. In like manner, the principle is especially applicable to cab or 55 speed control of trains at railway crossings, whereby the entry of one train into a cross-

ing block stops all transverse traffic while permitting the train in the crossing block to be controlled in the usual manner by the train ahead. 60

The invention is illustrated herein in connection with train carried devices which are selectively controlled by periodic currents of different frequencies, by circuits external to the train, or track circuits, having means for 65 producing a current or currents of such frequencies as are desired to selectively operate the particular device on the train which is to make the indication. In its preferred form, the system embodies a clearance device on 70 the train which must be operated before the train can proceed unlimited, and which is only operated when a current of "clear" frequency is applied thereto, whether automatically according to conditions in the same 75 block or ahead blocks, or manually by a tower operator, or according to the position of wayside semaphores. Upon receiving clearance, the train may proceed unlimited, but still other conditions tending to modify 80 an unlimited clearance may indicate to the engineer by the control device that he should proceed under caution, or may mechanically control the brakes or power, as will be understood. 85 Thus by this system, one characteristic current will produce clearance, for unlimited speed, and the train can only proceed at unlimited speed when it gets such clearance current, while other characteristic currents, depending in number upon the 90 conditions to be met, selectively used will make its own indication or produce its own speed in case the train is to proceed under control.

The present system is intended to be applied to existing standard track circuits and does not involve any substantial change in the present standard track relay circuits now used for wayside signals, and this invention can be installed without removing such signals. 95

In the accompanying drawing, Figure 1 shows a railway system embodying a preferred form of the invention,

Figure 2 shows a crossing,

Figure 3 shows a modified form of track circuit, and

Figure 4 shows a manual control.

In Figure 1, A represents a block having the track rails 1, 2, track relay 3 connected 110 across the rails, provided with armature 4 and supplied by battery 5 connected at one

- end to rail 1 by wire 6 and at the other end to the rail 2 through armature 7 of track relay 8 in block B, wire 9, contact 10, harmonic vibrator 11, wire 12, vibrator magnet 13 and wire 14. W represents a train in block B, which has caused relay 8 to drop armature 7. If there is no train in block B, the relay 8 holds up the armature 7 so that the circuit for relay 3 instead of going by wire 9 goes from armature 7 to contact 16, then by wire 17 to contact 18 through harmonic vibrator 19 of different periodicity or frequency than vibrator 11, then by wire 20 through magnet 21 to wire 14.
- When there is no train in either block, armatures 4 and 7 will be up, throwing magnet 21 in series with relay 3, but the resistance and ampere turns of magnet 3 are so high relatively to those of magnet 21 that the latter will not attract its vibrator 19. When there is a train, as W, in block B, which drops armature 7, magnet 13 is similarly in series with relay 3 but not energized sufficiently to attract vibrator 11.
- The entry of a train into block A short-circuits relay 3, allowing sufficient current to now flow through magnet 21, when there is no train in block B, to attract vibrator 19. This opens the circuit at contact 18 and causes a periodic current to be impressed from battery 5 in the circuit starting from the battery through wire 6, rail 1, the train axle to rail 2, wire 14, magnet 21, vibrator 19, wire 17, armature 7 to battery 5. If there is a train in block B, as shown herein, the magnet 21 is cut out at contact 16 and magnet 13 is thrown into the circuit by armature 7 at contact 22. In order to prevent any leakage of periodic current through the relay 3 when there is a train in block A, each relay circuit is provided with a reactance coil 24 which chokes the periodic current produced by the vibrators 11, 19, but does not interfere with the passage of track current when the vibrators are at rest.
- Vibrator 19 is called the clearance vibrator because this commences to vibrate as soon as a train enters block A if there is no train in block B, and thus indicates to the engineer by means of train circuits hereafter to be described, that block B is clear. If there is a train in block B and one in block A a vibrator 11 operates in A to control block A and vibrator 25 for train W in block B, and inasmuch as vibrator 11 has a different frequency from vibrator 19, it causes a different indication to be made on the train to notify the engineer of the danger condition in or ahead of block B. The vibrators 11 and 19, and others to be described, are shown of different design in order to indicate different frequency.
- Block B is herein shown as consisting of a curve where it is desired not only to indicate to the engineer that speed must be limited,
- but also to allow him to proceed if already within the limit. This is accomplished by substituting for the vibrator 19 having a clearance frequency a vibrator 25 having a still different frequency, and in placing on the train a third device which will be responsive only to the frequency of vibrator 25. Thus by simply changing the frequency of the track current, a different indication can be made on the train. Such an indication will, in the manner hereinafter explained, automatically limit the train to a predetermined speed, as thirty miles per hour, and the same means can operate an alarm, shut off the power, and make a certain signal. The train thus controls itself in its own block, but as will appear later, the speed control devices do not affect the engineer's volition as long as he keeps within the predetermined operating conditions laid down for him by adjustments of the apparatus. Block B at the front end is provided with a battery 5 leading through armature 7 of track relay 3 in block C and connected to magnets 21, 13 and vibrator 11 as before described for block A, it being seen that the vibrator 11 in block B performs the same function for a train therein when there is a train in block C, as vibrator 11 in block A does for a train therein when there is a train in block B.
- In block C is shown a drawbridge 27, which when open, or about to be opened, cuts the rails so as to first of all deenergize track relay 3 in this block and drop its armature 7, which is equivalent to a train being in block C, and causes the control vibrator 11 in block B to operate if a train is in block B, or as soon as one enters block B. If the drawbridge opens after a train has entered block C, a danger indication is made on the train in block C because neither the vibrator 11 nor the vibrator 19 in block C can operate, and the train will either get a signal for an emergency stop, or will be stopped by the air brake as will be described later.
- In Figure 2 is shown a grade crossing for two railroads, wherein the first train entering the crossing block controls all trains on the cross tracks, each crossing block being associated with a preliminary block divided into two sections. This sectional preliminary block has to function as an ordinary block and is consequently controlled by the crossing block on its line, which is the block ahead. Also, this sectional preliminary block functions in its first section to slow down a train approaching the crossing block when a train on the other railroad is already in the crossing block and the second section of this preliminary block is so controlled as to stop a train therein approaching the crossing, when a train on the other railroad is in its crossing block. Two double track roads crossing each other are illustrated

herein with sufficient wiring so as to show the reciprocal control by trains on one track over those on the other approaching the crossing in either direction.

5 "E" and "W" represent east and west bound tracks, and "N" and "S" represent north and south bound tracks respectively, the trains moving in the directions of the arrows, and "X" being the general crossing point. Track E is made up of sectioned block F, crossing block G and a succeeding block H, which is an ordinary block similar to block A. Track W is composed of sectioned block K, crossing block L and ordinary block M. Track S is composed of sectioned block O, crossing block P and ordinary block Q similar to block A. Track N is composed of sectioned block R, crossing block T and ordinary block V, but these 20 blocks are not all shown as reciprocally wired, in order to avoid unnecessary complication.

For purposes of illustration, a south bound train *a* is in crossing block P and a following train *b* is in block O, while an each bound train *c* is in the control section of block F, and a west bound train *d* is in block K. Blocks F, O, R and K are sectioned by means of insulations 28 in one rail 30 between one of the terminals of the track relay and one of the battery terminals, so that the clearance current, the control current, or no current at all will be supplied to a train according to the condition of its own track ahead and also according to the conditions on the other road. Since train *a* is already in crossing block P, the conditions are that train *c* can proceed under control in block F until it passes the cut section 40 28 and then it must stop in the remainder of block F. The same conditions apply to train *d*. Although train *a* is in the crossing block P, it must still be controlled by the condition of block Q, and train *b* must 45 at all times be subject to control according to the condition of block P. At this time, north bound trains in blocks R, T and V are to be similarly controlled.

Preliminary block F is provided with a 50 battery 30, and the usual track relay 3 shown in Figure 1. On the entering side of insulation 28 is a wire 31, which is connected to vibrator 32, thence by wires 33, 34 to armature 35 of relay 36 belonging to block P, thence continuing by wire 37 back to wire 38 through magnet coil 39 belonging to vibrator 32 to battery 30, thence to upper rail in block F, thence to and through train *c* and on south rail to wire 31. Train *a* in block P having dropped armature 35, control vibrator 32 thus applies current from battery 30 of a predetermined frequency to the first portion of block F, thus indicating control to train *c*, or causing the air brake 60 to slow down train *c* to a certain speed as

hereinafter described. When train *c* passes insulation 28, it loses the control current and also clearance current, and thus must stop as long as there is a train in block P or block T. Wire 40 leads from the south rail 70 of the second section of block F to a contact controlled by armature 401 of relay 36 in block P, which being down owing to train *a*, opens wire 41 which leads to armature 42 of relay 43 belonging to block T. Armature 42 when up contacts with wire 45 which leads back to clearance vibrator 46 in block F thence by wire 47 through magnet 48 and wire 49 to armature 50 belonging to relay 51 in block G thence by wire 52 to 80 battery 30. The armatures 42 and 401 being in series, train *a* in block P, or a train in block T thus opens the circuit of clearance vibrator 46 in block F, so that train *c* can get no clearance as long as there is a 85 train either in block P or block T, nor can it get control since vibrator 32 can get no current. Likewise, if there were a train in block G only, it would drop armature 50 and hence prevent any clearance to train *c*, 90 on the other hand with north and south tracks clear would give the control of vibrator 402. If there is a train in block G ahead of train *c*, with no trains in block P or T then relay 51 drops armature 53 so as 95 to make a circuit through magnet 39 from battery 30 by wire 38, contact 54, armature 53, wire 55, wire 34, connection 403, wire 33, vibrator 32 and wire 31 to rail of section F getting the control of vibrator 32 and the 100 same control after passing insulation 28 through wire 40 instead of 31.

If there is no train *a* in block P, the armatures controlled by relay 36 will all be up, so that by leading wire 57 from wire 31 to 105 armature 401, a bridge is formed around insulation 28 between wires 40 and 31, so that unless there is a train in block P, the insulation 28 is ineffective and the entire block F acts as an ordinary block without the cut 110 section.

Train *a* in block P has set block F so as to 115 control train *c* as far as insulation 28, and to stop train *c* as soon as it goes beyond insulation 28, and also performs the same function for train *d* in block K, it being observed that periodic current is not applied to any block except by the presence of a train, creating its own clearance or control current, as the case may be, or a train in the block ahead, or equivalent effect created mechanically or otherwise to produce the results desired without a train ahead,—a phantom condition. This is the principle used in the crossing and created on blocks F and K by the dropping of relay 36 of block P by the entrance of train *a*.

Train *a* in block P thus, in a sense, exercises the same control upon train *c* in block F as a train in block G would normally exer- 130

cise on train *c*, and the apparent complexity of circuits is due to the necessity of not only causing train *a* to control block F for two functions, control and stop, and block K for the same two functions, but also normal control of block O in the rear on its own line.

In other words, the preliminary sectioned blocks F, K, O, and R, are reciprocally controlled by trains in the crossing blocks, in such manner as to at all times preserve safety of operation and only to positively clear a train when it should be cleared.

By making the preliminary and crossing blocks of different lengths, it is insured that the train which first enters the crossing block will prevent trains on the other road from entering the crossing block, or else signal them not to enter depending upon the nature of the train circuits.

20 The clearance for block O is from battery 60 through wire 61 to armature 62, wire 63, magnet 64, clearance vibrator 65, wire 661, to the cut-rail section of block O, south track, thence by south rail, train and north rail and wire 661 to battery, this circuit being open at armature 62 by train *a* there can be no clearance. At the same time, train *a* makes the control circuit for block O from battery 60, wires 61, 67, magnet 68, wire 69, armature 70, wire 71, control vibrator 72 and wire 73 to wire 661, to south rail cut-rail section, thence by south rail, train, north rail and wire 66 to battery.

In addition to controlling block F, train *a* also controls block K in a similar manner. Train *d* is now getting control current through vibrator 75 from battery 76 as follows: wire 77, magnet 78, wire 79, armature 80 of relay 36, wire 81, control vibrator 82 for block K by wire 83, to the north rail of cut-rail section thence through the wheels and axle to the south rail, thence along the south rail and by wire 84 to the battery 76.

There is thus no clearance for train *d* if armature 90 of relay 36 is down when train *a* is in block P, nor when armature 88 of relay 43 is down by reason of a train in the crossing block T, nor when armature 94 is down owing to a train in block L.

50 If there is no train in blocks P, L, or T, the insulation 28 in block K is bridged and hence rendered inoperative, so as to enable train *d* to get clearance current throughout block K by means of wire 99 having a closed contact with armature 88 when relay 43 is energized, the other end of the wire 99 being connected to the other section of the cut rail in block K, the remainder of the circuit from armature 88 back to the battery 76 being the same as the clearance circuit above described through armature 94. Thus, this bridge circuit is opened either by armature 94 when there is a train in block L, or by armature 90 owing to train *a* in block P, or

by armature 88 when there is a train in block T.

On account of the complete wiring not being shown the wire 66 is shown as connected on both sides of the insulation 28 in block O, but with the complete wiring the connection of this wire attached to the south rail in the cut section of block O, i. e., that part next to the crossing block, will be cut, or its circuit broken, by another train in an opposing block only when conditions require, since the complete wiring would require that instead of becoming a part of wire connection 66 and making the cut section of rail ineffectual this wire would, in a manner similar to wire 40, be led through armatures on relay 51 of block G and 95 in block L.

As the wiring in block O is shown with a permanent bridge instead of an armature controlled bridge, the block O is shown with a condition which will not be present normally at crossings, but has to be permanently bridged to furnish some condition which on the drawing would allow and account for train *a* in block P. Unless wired as shown, it would be a loose end as its cut-rail section would not get any current of any kind, and train *a* never could pass it. The drawing shows block F properly wired.

Train *b* entering block O without any train in block P or G or L would (except for the fact that safe operating dictates a thirty mile maximum) normally get a clearance current from battery 60, but in order to limit the speed maximum in an approaching block, vibrator 65 is like that used for thirty mile control on a curve, and thence through armature 62, wire 63, vibrator coil 64. From vibrator 65, the current reaches the cut rail section along wire 66 and then to battery. The train will thus have only thirty mile maximum indication until it reaches the crossing block because of armature 401 on relay 36 being up.

When train *b* enters block O and there is a train in blocks G or L or both, and no train in block P, with complete wiring to armatures on relays 51 and 95, train *b* would be controlled at 15 miles by vibrator 72 to insulated point 28 in block O, and then stopped in the cut-rail section adjacent to block P.

As shown, with the same conditions, blocks L and G are not wired to affect blocks O or T and hence train *b* gets 30 miles maximum in block O and clearance in block P from vibrator 404.

The operation of the preliminary block will be understood from the following conditions:

1. Normal, when train *c* in the entering portion of block F will have maximum speed of 30 miles from reed 46 and the same speed

from reed 46 when in the exit section through wire 40, armature 401, etc. as long as armatures of relay 36 are up.

2. Cautionary, except when there is a train in block G just ahead. Train *c* now loses 30 mile maximum because of the dropping of armature 50 by de-energization of relay 51, but armature 53 drops and through reed 32 gives 15 mile control to train *c* in the entering section of block F. When train *c* goes into the leaving section of block F, it will stop owing to reed 32 losing its current. Thus, there is no possibility of two trains getting into block G either on the same line or different lines.

3. Cautionary, with a foreign train *a* controlling train *c*. Train *c* can proceed in the entering section of block F at 15 miles, on account of reed 32, and will stop when it gets into the leaving section of block F. As soon as train *a* passes into block Q, reed 46 will vibrate and permit train *c* to resume speed up to 30 miles, until it has entered block G whereupon if block H is clear, train *c* can get full clearance, but if block H is occupied, reed 402 will give 15 mile control to train *c*.

As a matter of precaution a train in the preliminary block should not have clearance, but be limited to a maximum speed. To effect this vibrators 46, 65 and 75 will have periods corresponding to the predetermined maximum. This will also serve to have the train at low speed in both sections of the preliminary block in case of an emergency application by a train controlling it from a foreign track. It is not desirable to bring a free running train to a quick stop by suddenly removing all control current from the rails. So this arrangement gives maximum, say 30 miles, then after getting controlled in first section of this block, a lower speed, as shown 15 miles, until passing insulation 28; then if clear on crossing and ahead it gets resumption of 30 mile maximum.

The vibrator 46 acts as a substitute for the clearance to limit the maximum speed in the entire preliminary block, even though other blocks on its own or the foreign line are clear. Control vibrator 32 works only for a train in the entering section of its preliminary block and does not operate after the train passes insulation 28, thus giving the first section 30 miles maximum normal with 15 mile control when there is a train ahead or on the foreign crossing track, and has no current only when out of order, or with a train in the second section in advance of insulation 28. This second section in advance of insulation 28 will have 30 miles when clear everywhere, and a dead stop in all other conditions. With any train in the crossing block, all other trains are positively prevented from entering, and the first train in has full liberty and is able to clear the

crossing for other traffic as quickly as possible. If for any reason the speed in the crossing block is to be limited, vibrators 404, 405, 406, 407 will be changed to those corresponding to the desired speed, and the clearance removed, but the construction shown which permits unrestricted speed in the crossing block is considered preferable.

The stopping of all trains under all conditions which are not normal and preventing any train getting into the crossing block unless conditions are perfectly normal, is brought about by depriving this exit section of all current of every nature in every case except normal, as is shown for it is supplied by one wire only, 40, and this somewhere in its line is cut and the circuit broken for the exit section in every condition except normal which is maximum 30 (or some other definite) miles.

This is exactly what happens on an ordinary block when a train runs, under control, into an occupied block, because it does not get either a clearance or any control current.

I consider this feature to be of fundamental importance inasmuch as the system thereby becomes completely self-detecting as a danger indication is necessarily made, or a stop effected, upon failure of either clearance or control current. Moreover, a battery failure in one block not only puts a train in the following block immediately under control but stops the train in its own block by depriving it of either clearance or control current. Self-detection is complete because while positive action is required to operate, a lack of any function to operate gives a negative or safety first control.

In Figure 3 is shown a modified track circuit in which the track battery 103 only operates the track relay 3. The control battery 5 is normally on open circuit by means of an armature 105 on relay 3 connected with wire 14 through wires 106 and 107 so that a train upon entering the block sets the control circuit in the preceding block by dropping armature 104 and sets its own clearance or control circuit by dropping armature 105. To prevent leakage of the pulsating current, the track battery circuit has its own reactance 108.

In Figure 4, is shown a simplified arrangement for manual control, where a tower man will be provided with a source of periodic current, such as an alternator 110, which supplied a frequency changer 111, connected through a switch 112 by wires 113, 114 to the rails, so that a frequency will be supplied to the train according to the position of the switch 112 and thereby make on the train an indication corresponding to the setting of the switch, the control corresponding to the automatic or a cab signal mechanical, visual or audible, or effecting some mechanical operation such as throttle, whistle, bell, etc.

For additional safety, the switch can be mechanically connected with a semaphore so as to have corresponding positions and operated simultaneously with it.

5 In the embodiment of the invention herein illustrated, the wheel axle carrying the periodic current constitutes the primary of a transformer, and the secondary consists of a wire 120 wound on a core surrounding the 10 axle in inductive relation to the primary. This form is only illustrative, as various other forms of train carried secondary circuits and methods of supplying current to a train from wayside circuits are known and can be used 15 herein without departing from the broad scope of the invention. The wire 120 is connected in series through magnets 121, 122, 123 on a closed circuit, there being a magnet for each different frequency of signaling current which is to be employed in the track circuits. Magnet 121 is the clearance magnet, 20 magnet 122 is a speed control magnet and magnet 123 is a different speed control magnet. Thus for instance magnet 123 may be 25 responsive to the frequency produced by vibrator 25 and by connections to be described reduce the train speed to thirty miles per hour on the curve in block B. The alterations through magnet 121 by a frequency 30 corresponding to that of vibrator 19, or those determined by the frequency changer, cause tuned reed 124 to vibrate, and thereby closes across contacts 125 the circuit of battery 126 through solenoid magnet 127, the fingers 125 and the reed 124. This energizes 35 magnet 127 and lifts valve 128 so as to cut off the supply of air from reservoir 129 through pipe 130 to valve 131 driven by the train axle. It will be seen that this air supply is only cut off when the clearance reed 124 vibrates. The vibrations which cause reed 124 to vibrate are ineffective upon the 40 other tuned reed 132 corresponding to the lower speed control such as ten miles per hour, and 133 corresponding to the thirty mile speed, or to corresponding indications. Reed 132 is connected in the circuit of battery 146 and magnet 147 so as to close the magnet circuit at fingers 237 whenever it 45 vibrates, while tuned reed 133^a closes the circuit of its magnet at fingers 138 whenever it vibrates, which correspondingly energizes magnet 148 and lifts armature 149. As many magnets 147, 148, etc., are provided as there 50 are reeds 132, 133^a, etc., there being a reed and a magnet for each frequency employed. 55 The valve 131 is geared to the axle or other part moving continuously whenever the train moves and at a rate varying and proportionate to the train speed, so that the 60 normally closed valve 128 admits no air pressure normally from air reservoir 129 through pipe 130 to the passage 132 as it presents its opening on revolving with the 65 train movement, because valve 128 is nor-

mally held closed by magnet 127 being energized from battery 126 by the vibration of reed 124 corresponding to "clearance" for we see that no action by the system takes place while operated within the fixed rules and hence "clearance" is the normal condition and all controls and stops are variations though it may be they are set for the normal (so-called) or fixed conditions for particular blocks.

70 When, however, conditions are not normal, i. e. when the clearance does not operate and magnet 127 is deenergized by the failure of current through points 125 because reed 124 has ceased to operate, then valve 80 128 opens and air from reservoir 129 rushes through pipe 130 and exits twice in each revolution into unit or fixed quantity chamber 134 once via port 135 and again through passage 133, while alternately, as will be 85 seen, the unit or fixed quantity chamber 134 will independently discharge its charge through port 135 and passage 136 into accumulation chamber 137 and again through passages 133 and 136 into 137. When the 90 valve 131 is at rest, no air is discharged from the reservoir 129, because the passage 132 does not furnish any direct connection from pipe 130 to passage 136. With valve 128 open, chamber 134 furnishes a measured 95 quantity of air twice in each revolution to accumulation chamber 137, and this air builds up pressure in chamber 137 sufficient to actuate the balanced piston valve 138 to the right so as to uncover one or more of 100 ports 139 and thereby open train line 140. A spring 141 tends to return valve 138 to the left sufficiently to normally hold ports 139 closed except when there is sufficient 105 pressure built up in chamber 137. In order to secure speed control, variation of speeds is fixed by the resultant between full air pressure of reservoir 129 into chamber 137 less a fixed exit according to the speed. The relief of pressure from chamber 137 is controlled through separately adjustable graduated valves 143, which valves are normally held closed and are positively opened by magnets 144, 150, 151 and 152, there being a magnet for each valve. The reliefs are 110 so adjusted, that at various speeds, each will allow a different fixed quantity of air to escape from chamber 137 while it is coming in, so that the valve 138 cannot open the train pipe, if the exit equals the intake 115 quantity, for then there can be no brake action for there can be no pressure built up in the accumulation chamber to open 140. 120 If now the train speed exceeds this predetermined speed, pressure is then built up 125 and the train pipe opened and the brakes applied, or the power cut off, until the speed is reduced sufficiently so that no pressure is built up and 138 is drawn back by spring 130 141 so that there is no opening from train

line 140 through 139. Thus as long as the engineer keeps within the speed specified, his control is not interferred with, but he is automatically slowed down to such speed 5 in case he fails to obey the rule, and then is free again to run within its limits specified.

Clearance being the normal, no air escapes from reservoir 129, but, whenever clearance does not operate, air is always going into 10 137, when the train is in motion, an excess of predetermined speed builds up pressure in 137 and means brake application; the predetermined speed or less means no pressure in 137 and hence no brake application.

15 Emergency or dead stop means all of the pressure of 129 into 137 and no exit of air from 137 because 143 does not operate to open the exit which it does only for control.

Operation of the clearance vibrator 124 thus actuates magnet 127 and constitutes an indication of one condition, in the case shown being the closing of valve 128 to cut off the air pressure from reservoir 129, since otherwise the pressure would build up in 25 chamber 137 and stop the train. This might be considered a danger indication in case of failure of this magnet 127 to operate, or parts controlled thereby, and when it operates, as a clear proceed indication.

30 The reed 132 when vibrating closes the circuit of battery 146 through a magnet 147, causing it to lift its armature to close the circuit of magnet 144, causing the relief valve 143 to open. This gives the control 35 speed, such as eight miles per hour, as will be determined by the adjustment of the relief valve 143. The tuned reed 133^a likewise controls the circuit of a magnet 148 connected to battery 146 and causes armature 149 to make the circuit of magnet 150, having a 40 relief valve set, for example, to enforce not over thirty miles per hour, such as might be used for the curve in block B. Other vibrators for other conditions would actuate 45 other magnets, such as 151, 152, so as to make as many different indications as there are frequencies. The circuit of magnet 127 may be provided with a white light for example, such as 156, the circuit of control 50 magnet 144 with another light, such as green, 157, and the circuit of magnet 150 with still another colored light, such as red, 158, so that the engineer will have visual signals to inform him of conditions, as well 55 as speed control. While the broad idea of a cab signal system is disclosed herein, a specific cab signal system is to be embraced in a separate application.

60 By this invention so long as the engineer confines his operation and control within the rules of the operating department, he may proceed throughout the entire system without the presence of control affecting him, but in case of violation, he will not only receive notice, but will have the control taken

away from him to be automatically released and restored as soon as the train is brought again within the limits of the rules. This system also takes care of its own failures, always on the safe side, because an open 70 clearance magnet circuit, either in the track or on the train, will stop the train. Any opening of the secondary circuit on the train will stop the train because there will be nothing to shut valve 128. If a track relay 75 fails, it applies control to the preceding block, but still enables a train in its own block to be cleared or controlled, as the case may be. If the circuits of indicator magnets, such as 147, 148, 144, 150, 151, are not 80 closed, the graduated needle valves do not open and the train stops. The moment a train comes within a faulty zone it will receive the control laid down by the operating department for such fault, or equivalent. Also, if a train is within a particular zone and the system fails to carry out the rules, instantaneous control of a predetermined nature for such condition is given, so that for all conditions a predetermined 90 control is always ready to act.

By this invention the following essential requirements of a control signal device for control from maximum to dead stop and automatic or non-automatic, the latter being 95 manual operation and the like while the former consists of operation by the presence or movement of a train, are characteristics of this system:

The apparatus is so constructed that the 100 removal or failure of any essential part, either of the normal block signal system or of this control system, would cause the display of a stop signal and the application of the train brakes.

The system can be installed on any railroad, with or without a block signal system, and installation with any block signal system may be made without in any way interfering with the operation or efficiency of 110 such signals.

The application of the train brakes is directly proportional to the speed and the system is so elastic that this element may be made to function according to any constant 115 or to an ascending or descending fixed series based upon operation conditions and if desired the relation may be to time or distance as well.

The system can be installed on any number of tracks in one railroad and is so elastic as to be capable of variation to meet a pre-determined control for every operation condition, and at the same time to control for perfect safety other trains at crossings and under smilar conditions be controlled by them.

The derailing of main line trains becomes unnecessary.

The electric circuits are so designed that 130

the occurrence of a break, cross or ground, or a failure of the source of energy in any of the circuits, will cause the display of the stop signal and the proper application of the train brakes.

10 The apparatus conforms to all recognized standards of clearance of rolling equipment and structures and will not be subject to damage therefrom. There are no vehicle and road-bed parts which have to come into operative relation with each other as the control on the train is effective by means outside of the train and independent of centrifugal governors, ramps, signaling third rails or other arrangements such as have heretofore been proposed. Conditions of speed, weather, wear of tracks or vehicles, oscillation and shock, due to such operative relation required by ramps, etc., are therefore eliminated in this system.

20 The system is capable of control by ordinary means used for indicating the condition of the block about to be entered, such as electric track circuit.

25 The system may be operated with direct current for track circuits or alternating track circuit system may be employed.

30 The engine apparatus is so constructed that it prevents the release of the brakes after the application for a dead stop until the cause for the application has been removed, or in case of the control application until the train is brought within the predetermined speed.

35 The system may provide, if desired, for special conditions, such as congested traffic, the continuous display of special indications in addition to the intermittent display of the fixed signals.

40 The apparatus is so constructed that it cannot constitute a source of danger of trainmen, any employees or passengers.

45 The apparatus is non-inductive, so that its application to a railroad where alternating current electricity is used as a propelling power, is not precluded.

50 The apparatus is so constructed that when the dead stop device has applied the brakes no one can release the brakes until the cause is removed.

55 The apparatus is so constructed that when the speed control device has applied the brakes for a maximum speed only, that the automatic control is automatically released as soon as the train reduces to the predetermined speed, thus avoiding delay by bringing the train to a dead stop, for reduced speed requirements only.

60 This system is so constructed and furnished with such apparatus:

65 That, it may be installed on any railroad, with or without a block signal system and without interference with any; it may be installed for any number of tracks; it is so elastic in its uses that it may be made to

control from the highest speed to a dead stop and perform any predetermined speed rules within these limits, whether required for operation of the train itself, the control of rear trains, crossing trains of other lines, 70

or any operating condition existing temporarily or permanently on the road bed whereby fixed speeds are desired for safety, economy or comfort; it may employ direct or alternating current and operate whatever 75 the motive power even to gravity movements; it uses no parts, such as ramps, requiring operative relation and therefore avoids failure due to weather conditions and faulty parts; it may operate both as stop 80 and control and as well to perform any operation possible by any engineman for safety of train and passengers or freight from throttle to whistle blasts of any number and duration; it may also in conjunction with 85

the control, or separately, serve to produce audible or visual signals in the cab alone, other places on the train, or both and also produce visual and audible signals on the road bed for public safety; it may be used 90

for telephonic or graphic communication with the engineer of a moving train for unlimited distances through road bed wire conductors similar to telegraph lines or for limited distances through the rails by trains 95

ahead depending upon the overlap apparatus; it is a continuous and absolute control which renders "safety first" absolute on failure or removal of any essential part or current, and is a perfect self-detector of all 100 faults; it is in practice a closed circuit continuous control through a fundamental clearance function and at the same time contains the main control circuits open, if desired, to save maintenance cost; as an accessory to signal systems it can be installed at 105

a small cost and maintained with present working forces; though a system is installed an unequipped engine, such as a switchyard engine, will be unaffected by it, if desired; 110 it is a so-called wireless system since only the rails are used for track and control circuits; and finally in its entirety will provide a system within whose limits of apparatus and operation a complete set of rules laid 115

down by the operating department may be resolved into electro-mechanism devices, giving continuous control, preventing violation without immediate and effective control from a dead stop to limit of speed and yet 120 at all times allowing the engineer to proceed unaffected so long as he remains within the rules resolved into the control at all times ready to assume command should he neglect, or be incapable of complying with 125 predetermined rules and at once upon the return of proper conditions of speed or safety he will be allowed to proceed, yet at all times, if desired, his defaults, and those of the system, may be registered and complete 130

operation records furnished the operation department.

It will be understood that the form of the invention shown herein is for illustration, 5 and that numerous modifications and changes may be made without departing from the scope of the appended claims.

What is claimed, is:

1. A railway system having normally inoperative means for producing a predetermined speed mechanically tuned, means controlled by pulsating current for releasing said first means, and a block having a source of pulsating current of a frequency to actuate said tuned means for controlling said release upon entry of the train into the block.

2. A railway system embodying crossing tracks each having a crossing block and a preliminary block, the preliminary block of one track having means for restricting the speed of a train in one portion thereof and stopping the train in another portion thereof controlled by the condition of the other track.

3. A railway system embodying means for producing a predetermined speed controlled by pulsating current of predetermined frequency, a track crossing in advance of the point at which such predetermined speed is produced, and means whereby a train on such track crossing controls a train approaching the crossing beyond said point of predetermined speed.

4. A railway system embodying crossing tracks, a preliminary block in at least one of said tracks, means for supplying periodic current to the rails of said preliminary block, and means whereby a train at the crossing on the other track cuts off said periodic current from said preliminary block and stops a train therein in advance of the crossing.

5. A railway system embodying crossing tracks each having a preliminary block in advance of the crossing for causing a current through the rails to slow down a train at the entering end and stopping the train by cutting off said current at the end nearest the crossing when there is a train at the crossing.

6. A railway system embodying crossing tracks, a preliminary block in advance of the crossing having means for applying a periodic current across the rails controlled by a train therein and a train at the crossing on the other track, and means on the train including a device responsive to such current and a wheel driven valve for controlling the train speed.

7. A railway system embodying crossing tracks, a preliminary block in advance of the crossing having means for applying a periodic current across the rails controlled by a train therein and a train in advance,

and means acting to stop a train in said preliminary block when there is a foreign train at the crossing and to limit the speed when there is a train in advance at the crossing, said means including a device responsive to 70 said periodic current and a wheel driven valve.

8. A railway train having a plurality of magnets in a single closed series circuit, a vibratory reed of different period controlled 75 by each magnet, means for selectively producing in said circuit a current adapted to vibrate one of said reeds at a time, and a different speed control device controlled by each reed.

9. A railway train having a plurality of magnets, a vibratory reed of different period controlled by each magnet, means for selectively vibrating one reed at a time, an air brake controlling valve closed by vibration 85 of one of said reeds, and a separate speed control valve controlled by vibration of each other reed.

10. A railway train having a plurality of magnets, a vibratory reed of different period controlled by each magnet, means for selectively vibrating one reed at a time, an air brake controlling valve closed by vibration 90 of one of said reeds, and a separate speed control valve controlled by vibration of each other reed, said latter valves being controlled by relay devices in the vibrating reed circuit.

11. A railway system comprising rails, a source of current connected to one rail on one side and on the other through a magnet and a reed to the other rail, and means whereby a train on said rails causes said reed to vibrate.

12. A railway system comprising rails, a source of current connected to one rail on one side and on the other side through a plurality of magnets and reeds, a separate section having rails, and means whereby a train in one section causes one reed in its own section to vibrate, and a train in each section causes the other reed in said section to vibrate.

13. A railway system comprising rails, a relay connected across the rails, a source of current connected on one side to one rail to supply said relay and on the other side through a magnet and a reed to the other rail to form a closed series circuit, and means whereby shunting of said relay causes said reed to vibrate and produce a periodic current.

14. The combination with a track comprising two blocks, of a track circuit and train responsive relay for each block, a plurality of magnet coils in circuit with the winding of one relay and the armature of the other, a vibrator for each magnet, means whereby one vibrator is effective to produce a periodic current when said armature is up and the other effective when down, and a 125 130

device differently responsive to each vibrator.

15. The combination of a plurality of vibrators of different period adapted to supply currents of different periodicity, and means whereby one vibrator is effective with a clear condition ahead and the other is effective with a danger condition ahead.

16. A railway control system embodying a plurality of means for producing across the rails periodic currents of respectively different frequencies, train carried devices responsive respectively to said different periodic currents, a stop device held ineffective by one of said currents, and a speed control means including a continuously driven valve rendered effective to produce a given speed by another current.

17. A railway control system embodying a battery, a track relay supplied thereby, a vibrator magnet in the same circuit, a vibrator rendered effective to interrupt said circuit when a train drops said relay, a second magnet in a normally open branch of said circuit, a vibrator of different period in said branch, and means for opening said first circuit and closing said branch when said second vibrator is to be effective.

18. A railway control system embodying a battery, a track relay supplied thereby, a vibrator magnet in the same circuit, a vibrator rendered effective to interrupt said circuit when a train drops said relay, a second magnet in a normally open branch of said circuit, a vibrator of different period in said branch, means for opening said first circuit and closing said branch when said second vibrator is to be effective, and a train carried circuit responsive to either of said vibrators when effective.

19. A railway control system having a periodic primary circuit controlled by track conditions, means for supplying a current of periodicity varying according to the track condition, a secondary train carried circuit controlling a plurality of reeds responsive to respectively different frequencies of secondary current, stopping and speed control means controlled by said reeds so that one reed renders the stopping means ineffective and another produces a predetermined speed.

20. A railway control system having a periodic primary circuit controlled by track conditions, means for supplying a current of periodicity varying according to the track condition, a secondary train carried circuit controlling a plurality of reeds responsive to respectively different frequencies of secondary current, stopping and speed control means including a continuously driven valve controlled by said reeds so that one reed renders the stopping means ineffective and another produces a predetermined speed.

65

21. In a railway control system, a train having a source of fluid pressure, an axle driven valve, an accumulation chamber, a piston movable in accordance with pressure in said chamber to vary the train speed, a valve for cutting off said fluid pressure when speed is not to be limited, and means external to the train for closing said valve when speed is to be unlimited.

22. In a railway control system, a train having a source of fluid pressure, an axle driven valve, an accumulation chamber, a piston movable in accordance with pressure in said chamber to vary the train speed, a valve for cutting off said fluid pressure when speed is not to be limited, a vibratory reed controlling said valve, and means external to the train for producing a periodic current to vibrate said reed and close said valve when speed is to be unlimited.

85

23. In a railway control system, a train having a source of fluid pressure, an axle driven valve, an accumulation chamber, a piston movable in accordance with pressure in said chamber to vary the train speed, a valve for cutting off said fluid pressure when speed is not to be limited, a vibrating reed controlling said valve, means in the trackway for producing a current of predetermined frequency to close said valve, a relief valve for said chamber, and another reed and track circuit of different frequency for opening said relief valve to effect a predetermined speed.

90

95

Signed at New York city, in the county of New York and State of New York, this 7th day of January, A. D. 1918.
